CLAIM

The ornamental design for a reel seat for fishing rod, as shown and described.

DESCRIPTION

FIG. 1 is a perspective view of the reel seat for fishing rod;

FIG. 2 is a front elevational view thereof;

FIG. 3 is a rear elevational view thereof;

FIG. 4 is a top plan view thereof;

FIG. 5 is a bottom plan view thereof; and,

FIG. 6 is a side elevational view, the opposite side being a mirror image thereof.

UNITED STATES PATENT AND TRADEMARK OFFICE
CERTIFICATE OF CORRECTION

PATENT NO. : D341,408
DATED : November 16, 1993
INVENTOR(S) : Steven L. Grice

It is certified that error appears in the above-identified patent and that said Letters Patent is hereby corrected as shown below:

Title page, item [56] References Cited, the following should be inserted:
